CLAIM

The ornamental design for a phone stand with screen magnifier, as shown and described.

DESCRIPTION

FIG. 1 is a perspective view of a phone stand with screen magnifier showing my new design;

FIG. 2 is another perspective view thereof;

FIG. 3 is a front elevational view thereof;

FIG. 4 is a rear elevational view thereof;

FIG. 5 is a left side elevational view thereof;

FIG. 6 is a right side elevational view thereof;

FIG. 7 is a top plan view thereof;

FIG. 8 is a bottom plan view thereof;

FIG. 9 is a perspective view of the phone stand with screen magnifier where the phone stand with screen magnifier is in a configuration of use;

FIG. 10 is an exploded perspective view of the phone stand with screen magnifier;

FIG. 11 is another exploded perspective view of the phone stand with screen magnifier; and,

FIG. 12 is an enlarged view of portion 12 shown in FIG. 1. The broken lines in the drawings depict portions of the phone stand with screen magnifier that form no part of the claimed design.
